UNITED STATES PATENT OFFICE

EARL R. SWANSON, OF CHICAGO, ILLINOIS, ASSIGNOR TO CHICAGO-CLEVELAND CAR ROOFING COMPANY, OF CHICAGO, ILLINOIS, A CORPORATION OF DELAWARE

CAR ROOF

Application filed August 14, 1929. Serial No. 385,870.

My invention relates to roofs for railway cars and more particularly to car roofs of the flexible type.

As is well known, the sheets of a flexible type roof are arranged in spaced relation longitudinally of the car so that they may move relatively to each other and to the roof structure. Heretofore in this type of roof mullions and other similar means have been used to limit movement of the sheets longitudinally of the car and seam caps, which usually embrace each of the mullions, have been employed to connect the edges of the sheets on opposite sides of the mullions.

One of the objects of the present invention is to provide one means which serves to limit movement of the roof sheets longitudinally of the car and to connect the adjoining edges of adjacent roof sheets by spanning the spaces between them.

Another object of the invention is to provide an improved center cap for connecting the adjacent transverse seam caps disposed on opposite sides of the ridge of the roof.

A primary feature of the invention consists in providing a flexible car roof with transverse seam caps, each of which has a portion adapted to extend into the space between adjacent roof sheets to limit their movement longitudinally of the car.

Another feature of the invention resides in associating with roof sheets having upturned side marginal flanges, transverse seam caps respectively having depressed central portions adapted to be disposed between the neighboring flanges of adjacent roof sheets and with portions for respectively housing the said flanges.

A further feature of the invention consists in associating with the transverse seam caps, center caps respectively having portions cooperating with the portions of adjacent seam caps which are disposed between the adjoining edges of adjacent roof sheets and with the portions thereof which house the upturned flanges of the roof sheets.

A still further feature of the invention consists in providing the ridge end of each seam cap with an upstanding portion to prevent

water from seeping under the center cap or being blown into the car.

Other and more specific features of the invention residing in advantageous forms, combinations and relations of parts will herein-after appear and be pointed out in the claims.

In the drawings illustrating a preferred embodiment of the invention:

Figure 1 is a fragmentary plan view of a car roof embodying the invention, portions of the roof sheets being broken away.

Figure 2 is an enlarged sectional view taken on line 2—2, Figure 1.

Figure 3 is an enlarged fragmentary sectional view taken on line 3—3, Figure 1, the running board saddle being omitted.

Figure 4 is a sectional view taken on line 4—4, Figure 3, a portion of a bracket for the running board saddle being illustrated.

Figure 5 is a perspective view of the center cap and the adjacent end of one transverse seam cap, the parts being illustrated in a dis-associated position.

Figure 6 is a fragmentary sectional view taken on line 6—6, Figure 1.

Figure 7 is a fragmentary sectional view taken on line 7—7, Figure 1.

Referring more particularly to the drawings, 1 indicates the side plates of the roof structure, which, as is well known, are connected at their opposite ends by end side plates not shown. Each of the side plates are preferably of Z shape, having upper and lower oppositely projecting substantially horizontal flanges 2 and 3 connected by a substantially vertical web 4. The carlines 5, which may be of any suitable shape, extend transversely of the roof and rest at their opposite ends on the upper flanges 2 of the respective side plates, being secured thereto by any suitable means not shown.

Extending longitudinally of the car are the usual purlins 6 and ridge pole 7 which rest upon and are secured to each of the carlines by bolts 8.

Extending between the ridge pole 7 and each side plate of the roof structure are a plurality of sheets 10 which are arranged in spaced relation longitudinally of the car. At portions intermediate their edges the roof

sheets rest directly upon and are supported by the purlins 6, while at their ridge edges they are supported in recesses at grooves 11 formed in opposite sides of the ridge pole 7. At their eaves edges the roof sheets are supported by filler members 12 which extend between the carlines and are respectively interposed between the roof sheets and the upper horizontal flanges 2 of the side plates.

Secured to the outer face of each of the 10 filler members 12 by bolts 13 is a fascia strip 14 which may advantageously depend downwardly so as to overlap the outer face of the web 4 of the associated side plate. Adjacent the neighboring eaves edges of each of the 15 roof sheets is a flashing plate 15 which is interposed between each filler member and fascia, on the one hand, and the roof sheets on the other, a portion of each flashing plate being preferably bent downwardly to overlap 20 the outer face of the fascia 14.

At their eaves edges each of the roof sheets is provided with a downwardly projecting flange 16 which, when the sheets are in assembled position, are spaced slightly outward 25 from the adjacent flashing plates 15, while at their ridge edges each of the sheets is provided with an upwardly projecting flange 17. These ridge flanges 17 of the roof sheets are spaced slightly from the portion 18 of 30 the ridge pole formed by the recesses or grooves 11 thereof. Adjacent their side marginal edges each of the roof sheets is preferably provided with an upwardly offset portion 18 which is spaced somewhat above the 35 purlins 6. Each of these offset portions of the roof sheets terminates in an upwardly projecting flange 19 provided with return-bent portions 20. Adjacent the eaves edges 40 of the roof sheets the upwardly projecting flanges 19 preferably merge into the plane of the main body portions of the sheets, while at their ridge edges they connect with the flanges 17.

To connect or join the adjoining side edges 45 of adjacent roof sheets, transverse seam caps or members 21 are preferably employed which respectively span the spaces between the roof sheets. Each of these seam caps is provided with a depressed central portion 50 adapted to be positioned between the upwardly projecting flanges of associated roof sheets to limit movement of the latter longitudinally of the car. The depressed portion 55 of each seam cap comprises a web 22 and upwardly projecting portions or legs 23, the web being preferably disposed in the plane of the main body portions of the roof sheets so as to rest upon and be supported by the 60 purlins. At their upper ends the legs of the seam caps are respectively bent outwardly, as at 24, thence downwardly, as at 25, and then terminate in laterally projecting flanges 26 which contact with the upper surfaces of 65 the offset portions 18 of the roof sheets. It

will thus be seen that the legs 23 and the portions 24 and 25 of the seam caps afford means for housing the upwardly projecting flanges 19 of the roof sheets. From the form of the seam cap illustrated, it may be said to comprise one upwardly opening channel which is interposed between adjacent roof sheets and two downwardly opening channels which respectively house the adjoining upturned flanges of adjacent roof sheets. 75 These channel portions of the seam caps are so positioned that when the roof sheets are in their normal positions the distance between the upwardly projecting flanges 19 of the roof sheets and the legs 23 of the seam cap is substantially the same as the distance between the ends of the portions 20 of the flanges 19 and the adjacent portions 25 of the seam cap. The laterally projecting flanges 26 of the seam caps are so arranged 80 that they tend to exert a slight downward pressure upon the offset portions 18 of the roof sheets so as to prevent the passage or seepage of water between the seam caps and roof sheets, but it will be readily apparent 85 that should water be blown or otherwise pass in between the seam caps and roof sheets, the upturned flanges 19 of the latter will prevent the water from entering the interior of the car. 95

At their ridge ends each of the seam caps is formed with an upwardly projecting flange 27 which, in effect, constitutes a continuation of the legs 23 thereof. These flanges, as will hereinafter more clearly appear, adequately prevent water from getting into the car at the seam caps adjacent the ridge of the roof. As it is particularly desirable to form or stamp the seam caps from one blank or sheet of metal, their ridge flanges are 100 curved and fluted to take up the excess metal which would otherwise occur at these points. At their eaves edges all portions of each of the seam caps preferably terminate in substantially the plane of the web 22 so that 105 water will readily drain from the roof. These plane portions of seam caps may advantageously be flanged downwardly, as at 28, in spaced relation to the eaves flanges 16 of the roof sheets. 110

The seam caps may be respectively secured in place by bolts 29 which pass through the webs 22 thereof and are connected to anchor brackets 30 of angle shape, one leg 31 of each of the brackets being preferably horizontal to support the bolt and the other leg 32 thereof being substantially vertical and secured to the side structure of the roof by the bolts 13 heretofore described. The portion of the web of each seam cap immediately adjacent the aperture thereof for receiving the bolt 29 may be conveniently offset as at 33 and a ferrule 34 interposed therebetween and the horizontal leg of the anchor bracket 115 for properly supporting the cap. 120

Embracing the ridge pole at points substantially midway between each of the roof sheets longitudinally of the car, are a plurality of members 35, each of which is fashioned with downwardly projecting flanges 36 adapted to respectively engage the outer faces of the upwardly projecting ridge flanges 17 of associated roof sheets disposed on opposite sides of the ridge. These members, which may be secured to the ridge pole by bolts 37, serve to limit movement of the sheets 10 transversely of the roof, but the inner surfaces of the flanges 36 thereof are preferably curved to permit the sheets to pivot or rotate with respect to them as a center.

In addition to the transverse seam caps 21, longitudinal seam caps 38 are provided which connect the ridge ends of adjacent roof sheets on opposite sides of the ridge of the roof and each of the caps 38 merely extends from adjacent one offset portion 18 of each roof sheet to the other offset portion thereof. Each of the longitudinal caps is preferably of channel shape, having a substantially horizontal web 39 and downwardly projecting flanges 40 terminating in laterally projecting flanges 41 which contact with adjacent portions of the roof sheets.

At the points of junction of the transverse and longitudinal seam caps are the center caps 42 which may be conveniently secured in place by bolts 43 which extend through suitably formed apertures in the ridge pole. These bolts 43 may also be employed for securing a supporting bracket 44 of the running board saddle 45. Each of the center caps is fashioned with a substantially horizontal, continuously extending web 46 and two pairs of downwardly extending legs 47, thereby forming two channel portions adapted to respectively embrace the adjoining ends of adjacent longitudinal seam caps. The legs 47 of the channel portions preferably terminate in lateral flanges 48 overlyingly engaging the upper surfaces of the adjacent offset portions of the roof sheets and of the lateral flanges of the longitudinal seam caps.

Intermediate their channel portions each of the center caps is formed with portions similar in contour to the transverse seam caps which are adapted to embracingly overlap the portions of the latter adjoining the ridge of the roof. Each of these transverse seam cap co-operating portions is provided with a web 49, upwardly extending legs 50, oppositely projecting horizontal portions 51 and downwardly extending legs 52 which merge with and form a continuation of the lateral flanges 48 of the channel portions of the cap. The legs 50 are joined by a portion 53 which is curved similarly to the curved flange 27 of the transverse cap. Figure 5 of the drawings readily shows the manner in

which these portions of the center cap co-operate with the transverse seam caps; and as the former fit down over the latter, any water which may be blown or otherwise pass in between them will be prevented from entering the interior of the car by the ridge flange 27 of the seam caps.

From the foregoing it will be perceived that a transverse seam cap has been provided which serves the dual function of limiting longitudinal movement of adjacent roof sheets and spanning the spaces between them, and that the improved form of center cap which has been disclosed serves to efficiently perform its intended purpose.

I claim:

1. In a railway car, the combination with purlins, of roof sheets arranged in spaced relation longitudinally of the car, and seam caps respectively spanning the spaces between adjacent roof sheets, each of said seam caps having a depressed portion interposed between the adjoining edges of adjacent roof sheets for limiting movement of the latter longitudinally of the car, said depressed portions of the seam caps being in supporting engagement with the purlins.

2. In a railway car, the combination with purlins, of a plurality of roof sheets arranged in spaced relation longitudinally of the car in supporting engagement with said purlins, and seam caps respectively spanning the spaces between adjacent roof sheets, each of said seam caps having a portion interposed between the adjoining edges of adjacent roof sheets, said portion comprising a web and upwardly projecting legs, said web being disposed substantially in the plane of the main body portions of the roof sheets and in supporting engagement with the purlins.

3. A roof for a railway car involving a plurality of roof sheets arranged in spaced relation longitudinally of the car, each of said sheets adjacent its opposite sides being offset upwardly and terminating in substantially upright flanges, and a plurality of seam caps for respectively spanning the spaces between the roof sheets, each of said seam caps comprising a web portion disposed intermediate the adjoining upright flanges of adjacent roof sheets and being disposed substantially in the plane of the main body portions of the roof sheets, said web terminating in portions forming housings for the upright flanges of the adjacent roof sheets, said housings being formed with laterally projecting flanges respectively disposed in planes above the web of the seam cap and arranged to contact with the adjacent offset portions of the associated roof sheets.

4. A roof for a railway car comprising a plurality of roof sheets arranged in spaced relation longitudinally of the car on opposite sides of the ridge of the roof, seam caps respectively having depressed portions

interposed between the adjoining edges of adjacent roof sheets, said depressed portion of each seam cap adjacent the ridge of the roof being flanged upwardly, and a plurality of center caps respectively having portions disposed within the depressed portions of associated seam caps, said portions of the center caps affording a housing for the ridge flanges of the seam caps.

5. A roof for a railway car involving a plurality of roof sheets arranged in spaced relation longitudinally of the car on opposite sides of the ridge of the roof, the side marginal edges of each of the roof sheets terminating in upturned flanges, seam caps on each side of the ridge of the roof for spanning the spaces between the roof sheets, each of said seam caps having a depressed central portion for limiting movement of adjacent roof sheets longitudinally of the car and portions for respectively housing the adjoining upturned flanges of adjacent roof sheets, and center caps for respectively connecting the adjacent seam caps on opposite sides of the ridge of the roof, each of said center caps having portions generally conforming to the contour of the seam caps.

6. A roof for a railway car involving a plurality of roof sheets disposed on opposite sides of the ridge of the roof, the sheets on each side of the ridge being arranged in spaced relation longitudinally of the car, each of said roof sheets being fashioned with upturned flanges, seam caps spanning the spaces between the roof sheets, each of said seam caps having a central web and upwardly projecting legs disposed intermediate the adjoining upturned flanges of adjacent roof sheets, the legs of each seam cap terminating in portions forming housings for the upturned flanges of the adjacent roof sheets, each of said seam caps adjacent the ridge of the roof being fashioned with a flange forming a continuation of the legs thereof, and center caps for respectively connecting the adjacent seam caps on opposite sides of the ridge of the roof, each of said center caps having a portion for housing the ridge flanges of associated seam caps.

50 7. A roof for a railway car involving a plurality of roof sheets disposed on opposite sides of the ridge of the roof, the sheets on each side of the ridge being arranged in spaced relation longitudinally of the car, seam caps on each side of the ridge of the roof for spanning the spaces between adjacent roof sheets, each of said seam caps having a depressed portion interposed between adjoining edges of adjacent roof sheets, the depressed portion of each seam cap being fashioned with an upwardly projecting flange adjacent the ridge of the roof, and center caps having portions respectively embracing the upwardly projecting flanges of adjacent seam caps.

8. A roof for a railway car involving a plurality of roof sheets disposed on opposite sides of the ridge of the roof, the sheets on each side of the ridge being arranged in spaced relation longitudinally of the car, seam caps on each side of the ridge of the roof for spanning the spaces between adjacent roof sheets, each of said seam caps adjacent its ridge end being fashioned with an upwardly projecting curved flange, the said flange being provided with a plurality of corrugations, and center caps respectively having portions for co-operating with said upturned flanges of adjacent seam caps.

9. A roof for a railway car involving roof sheets arranged in spaced relation longitudinally of the car on opposite sides of the ridge of the roof, each of said roof sheets having upwardly projecting side marginal flanges and ridge flanges, transverse seam caps for respectively spanning the spaces between adjoining side marginal flanges of adjacent roof sheets, each of said seam caps having a portion interposed between the associated roof sheets for limiting movement thereof longitudinally of the car, longitudinal seam caps respectively housing the adjoining ridge flanges of adjacent roof sheets, and center caps for respectively connecting the transverse and longitudinal seam caps, each of said center caps having channel-shaped portions cooperating with adjacent longitudinal seam caps and portions co-operating with the said interposed portions of adjacent transverse seam caps

In testimony whereof I affix my signature.
EARL R. SWANSON.
